(57) **CLAIM**

We claim the ornamental design for a door guard for refrigerator, as shown and described.

DESCRIPTION

FIG. 1 is a front perspective view of a door guard for a refrigerator showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top view thereof;

FIG. 7 is a bottom view thereof;

FIG. 8 is a perspective view thereof showing the guard in an “open” position rotated about a hinge axis; and,

FIG. 9 is a perspective view thereof showing the guard with its lid open.

The broken lines in the figure drawings represent unclaimed environment only and forms no part of the claimed design.
